MACHINE FOR FABRICATING METALLIC LADDERS

Joseph Anthony Mase, Detroit, Mich., assignor to International Steel Company, Evansville, Ind., a corporation of Indiana

Application August 27, 1952, Serial No. 306,577

6 Claims. (Cl. 219—2)

1

My invention relates broadly to a method and means for fabricating steel ladders especially adapted for railway car use and particularly to a machine and method for fabricating steel ladders.

One of the objects of my invention is to provide a method for fabricating steel ladders for freight car use by the hot upsetting of the metallic ladder rungs with respect to the steel angles forming the sides of the ladder.

Another object of my invention is to provide a method for fabricating steel ladders using angle members as side supports and steel rods as ladder treads which involves the hot upsetting of the opposite ends of the ladder treads for securing the ladder treads in the angle members.

Another object of my invention is to provide a construction of machine for fabricating railway car ladders from steel angles forming the sides of the ladder and steel rods forming the treads of the ladder in which successive operations for clamping, forging, quenching and unclamping the ladder in a hot upsetting machine are performed automatically subject to manual placement and guiding of the ladder in the forging of successive ladder rungs between the steel angles.

Still another object of my invention is to provide a program control circuit for a hot upsetting machine particularly adapted for the fabrication of steel ladders whereby successive ladder rungs are clamped in position with their opposite ends extending through aligned perforations in the flanges of angle members forming ladder stiles and the projecting ends of each rung successively subjected to the passage of heating current for raising the rungs to a suitable heat whereby the opposite ends of the rungs may be axially subjected to pressure for upsetting the material thereof and securing the rung with respect to the ladder stiles.

Another object of my invention is to provide an arrangement of timing means for the electrical and compressed air control means of a hot upsetting machine for fabricating railway car steel ladders whereby steel ladder stiles and steel rungs may be clamped with the ends of the rungs projecting through perforations in the flanges of the stiles, the ends of the rungs electrically heated, axial pressure applied to the ends thereof for upsetting the ends of the rungs with respect to the ladder stiles, the electrical heating current and pressure removed and the ladder unclamped for manual displacement to the next succeeding operating position for successively securing the rungs in position.

2

Still another object of my invention is to provide adjustable means for regulating the positions of the clamping means for the stiles of a railway car ladder while ladder rungs are being forged with respect thereto by the timed application of electrical current and pressure at projecting ends of the rungs which are assembled through the coacting ladder rungs.

A further object of my invention is to provide a mechanism for hot upsetting machines for fabricating steel ladders including an arrangement of electrodes which may be clamped under the action of pneumatic pressure for maintaining the ends of the ladder rungs in position through associated ladder stiles while the ladder rungs are being subjected to the passage of heating current and the ends subjected to axial pressure for securing the rungs in position in the ladder stiles.

A still further object of my invention is to provide a construction of machine for forging the ends of the transverse steel treads into secured relation with the perforated flanges of longitudinally extending steel angle members which involves the application of axial pressure through the threads toward the angle members, utilizing forming dies the heads of which are equipped with quenching means for effecting a sudden drop in temperature after each forging operation for insuring the rapid processing of the ladder through the machine.

Other and further objects of my invention reside in the method of operation and construction of hot upsetting machine by which steel ladder treads may be forged into secured relation with steel ladder stiles for the rapid fabrication of railway car ladders as set forth more fully in the specification hereinafter following by reference to the accompanying drawings, in which:

Figure 1 is a front elevational view of the automatic hot upsetting machine of my invention; Fig. 2 is a top plan view of the machine illustrated in Fig. 1 showing particularly the manner of guiding the longitudinally extending angle members with the ladder treads extending loosely through the spaced perforations therein preparatory for introduction into the hot upsetting machine of my invention; Fig. 3 is a side elevational view of the machine shown in Figs. 1 and 2 showing particularly the adjustable means for elevating the ladder stiles to a position in which the transverse rungs loosely carried therein may be introduced into the hot upsetting machine with the ends of the rungs axially aligned with the outside head forming dies; Fig. 4 is an enlarged transverse vertical view through the ma-

3

chine of Fig. 3 on line 4—4 thereof; Fig. 5 is a transverse vertical sectional view on an enlarged scale taken on line 5—5 of Fig. 3 with certain of the parts shown in elevation; Fig. 6 is a plan view; Fig. 7 is a vertical transverse sectional view taken substantially on line 7—7 of Fig. 5; Fig. 8 is a detail view illustrating the adjusting mechanism with certain of the parts shown in section; Fig. 8a shows the assembly of the adjusting mechanism illustrated in Fig. 8; Fig. 9 is a fragmentary vertical sectional view looking in the direction of arrow A in Fig. 8; Fig. 10 is a fragmentary sectional view through one of the outside head forming dies shown in clamped relation to an inside head forming die, the dies being shown in position just after the completion of a hot upsetting operation and illustrating particularly the means for quenching the outside head forming die; Fig. 11 is a schematic diagram illustrating the programmed operation of the air control system in the hot upsetting machine of my invention; Fig. 12 is a schematic diagram of the program control circuit employed for timing the application of heating current to the ends of the treads while in clamped position between the ladder stiles for effecting an upsetting operation; Fig. 13 is a theoretical diagram showing the manner of applying the heating current to the ladder rungs under control of the circuit illustrated in Fig. 12; Fig. 14 is a theoretical diagram of the electrical current path through the ends of the transverse ladder treads and the outside head forming dies in accordance with my invention; and Fig. 15 is a transverse sectional view through the ladder rung as finally secured in the ladder stiles in accordance with my invention.

My invention is directed to a method of making steel ladders particularly adapted for railway car installation and to the construction of a machine for fabricating such steel ladders. I provide an arrangement of resistance bridge hot upsetting machine which employs a pair of axially disposed outside head forming dies adapted to be moved inwardly toward each other under pressure and a pair of electrodes adapted to be moved downwardly in a vertical direction under pressure in coplanar alignment with the axes of the advancing outside head forming dies and in proportion to the movement thereof for conjointly clamping the steel rung of a ladder resting loosely and transversely through longitudinally spaced angle members forming the ladder rung stiles. The loosely assembled ladder rung positioned in the ladder stiles is introduced in successive positions between the head forming dies and the pair of electrodes. The pair of electrodes grip the ladder rung interiorly of the flanges of the ladder stiles while the outside head forming dies establish pressure connection with the projecting ends of the ladder rungs. The alignment of the ladder stiles and the loosely arranged ladder rungs therein is effected manually, but, thereafter all operations are programmed automatically.

When the ladder stiles and the associated projecting ladder rung are firmly clamped in position the opposite ends of the ladder rung are subjected to the passage of electrical current which raises the temperature of the ends of the ladder rung to a red heat. When a flow condition of the steel is reached, the inwardly advancing outside head forming dies apply axial inward pressure to the rung. The electrodes which grip

the ladder rung in a position spaced from the interior sides of the flanges of the angle members constituting the stiles coact with anvils and form therewith an inside forming die whereby the material of the rung is upset in a position both inside and outside of the flanges of the ladder stiles, thereby firmly fastening the rungs in the ladder stiles. When the forging operation is completed the outside head forming dies effect a blast of air against the upset ends of the rungs suddenly cooling the rungs and setting the material thereof with respect to the ladder stiles. The program mechanism then effects a withdrawal of the outside head forming dies, a retraction of the electrodes and the release of the clamped stiles enabling the stiles to be moved to the next succeeding tread forging position for effecting a repeat operation. The total fabrication time for each ladder is but a small fraction of the time required for the production of conventional steel ladders.

Referring to the drawings in more detail, reference character 1 designates the frame structure of the hot upsetting machine of my invention which includes a central arch structure 2 which serves to support the vertically depending, spaced electrode operating cylinders 3 and 4. The electrode operating cylinders 3 and 4 control the depending electrode carrying piston rods 5 and 6 which suspend the electrodes 7 and 8 which grip the upper surface of the ladder rung 9 and provide part of the inside forming die for allowing the upsetting of the material of the ladder rung 9. The other portion of the inside forming die is constituted by anvils 10 and 11 aligned with the electrodes 7 and 8, respectively, on the inside of the flanges of the angle members 12 and 14, constituting the sides of the ladder.

The angle members 12 and 14 are fitted to the hot upsetting machine along a table shown at 15 in Figs. 1 and 2. The table 15 is erected on an angular iron frame 16, supported from the floor adjacent one end of the machine and supported by bracing members 17 from the top of the frame 1 of the hot upsetting machine. The top of the frame 1 is provided with spaced mounting means shown at 18, 19, 20 and 21 disposed forwardly and rearwardly of the arch structure 2 and in alignment with the angle members 12 and 14 being guided through the hot upsetting machine along table 15. The spaced mounting means are each adjustable in a vertical direction for properly supporting the angle members in positions in which the successive ladder rungs 9 may be gripped between electrodes 7 and 8 and anvils 10 and 11. That is, each of the spaced mounting means 18—21 includes a central screw threaded head therein shown at 18a, 19a, 20a and 21a, which may be elevated or lowered to accurately guide the angle members 12 and 14 in the course of the movement thereof through the hot upsetting machine. The central screw threaded heads include vertically adjustable supports 13b—21b, which operate in vertical paths within guides 18c—21c. The supports are projectible in a vertical direction by means of a mechanical linkage shown more clearly in Fig. 4 under control of an air supply cylinder 22 which controls the piston rod 23 connected at its center with the two laterally extending links 24 and 25. The laterally extending links 24 and 25 are pivoted at the inner ends thereof at 26 and connect with piston rod 23. The links 24 and 25 are pivotally mounted at 27 and 28 with respect to the frame 1 and have their outwardly extending ends piv-

totally connected through lost motion connections 24a and 25a with the lower ends of the adjustable supports 18b and 19b, whereby air supplied to cylinder 22 moves piston rod 23 downwardly, ejecting the central screw threaded heads 18a and 19a upwardly, engaging the flanges of the angle members 12 and 14 for elevating the angle members into a position in which the ladder rung 9 may be clamped between electrodes 7 and 8 and anvils 10 and 11. The identical remote end of the machine adjacent the spaced mounting means 20 and 21 is similarly constructed, and the central screw threaded heads 26a and 27a projected upwardly under control of the cylinder shown at 30 in a manner similar to the operation described in connection with cylinder 22.

The frame 1 of the machine has laterally extending supports thereon serving as mounting means for the oppositely disposed air controlled clamping cylinders 31 and 32, which are aligned on opposite sides of the arch structure 2 and in alignment with the outside head forming dies shown at 33 and 34. The outside head forming dies are cylindrically constructed as shown more clearly in Fig. 10, in which the outside head forming die 34 is shown as constituted by a cylindrical member having hollow tubular interior 34a externally screw threaded on its end 34b to engage the interior screw threads formed in the transverse block 35 to which transverse movement is imparted by operation of the piston in cylinder 32. Each of the head forming dies is cooled by an internal air blast conducted through a tubular member such as 34c in Fig. 10 connected to supply a blast of air from the air source connected through port 34d from which the air strikes the inside of the end wall of the hollow outside head forming die and is thereafter exhausted through discharge port 34e. A symmetrical construction is provided on the opposite side of the machine where outside head forming die 33 is coupled to the moving piston of cylinder 31 through block 36. Transverse guides 37 and 38 are provided for insuring the lineal movement of the outside head forming dies toward and away from the angle members as they are passed through the machine. The setting of the position of the outside head forming dies 33 and 34 is accurately adjusted by means of adjusting screws 39 and 40 mounted in bracket members 41 and 42 adjacent opposite ends of the frame 1 and connected with the casings of the air controlled clamping cylinders 31 and 32 for shifting the cylinders transversely in guides represented at 43 and 44 in Figs. 2 and 3.

In addition to the air actuated cylinders 22, 30, 31 and 32, there is also provided an ejector air controlled cylinder 45. The ejector air controlled cylinder 45 operates an adjustable piston rod 46 which is pivoted at 47 to a pair of links 48 and 49 arranged in the form of a Y. The ends of links 48 and 49 pivotally connect with the inner ends of a pair of ejector bars represented at 50 and 51. The outer ends of these bars extend through guides 52 and 53 supported in aligned positions on arch structure 2, so that the bars 50 and 51 are guided in a plane transverse to the direction of movement of the angle members 12 and 14 through the machine. The ejector bars 50 and 51 carry guide shoes 54 and 55 adjacent their bottom faces, which rest upon the mounting plates 56 and 57. The mounting plates 56 and 57 are in turn spacially adjustable on frame support 58 between guides 59. Operation of piston rod 46 serves to project or retract 75

the ejector bars 50 and 51 in a lateral direction and simultaneously engage the shoes 60 and 61 with the inside surface of the webs of the angle members 12 and 14 for facilitating the pressing of the angle members against the forces applied by the outside head forming dies 33 and 34 and insuring the upsetting of the metal of the rungs represented by rung 9 and the flow of the metal over both the inside and outside surfaces of the web of the angle member immediately surrounding the apertures through which the rungs project.

In addition to the foregoing air control cylinders, air control cylinders 62 and 63 are provided adjacent the front of the machine mounted on brackets 64 and 65 carried by the arch structure 2. The air control cylinders 62 and 63 operate transversely disposed bars 66 and 67 carrying anvil members 68 and 69, operative to engage the inner faces of the webs of the angle members 12 and 14 adjacent the position of entry of the angle members into the forging zone of the machine.

On opposite sides of the arch structure 2 there is provided centering lever arrangements for insuring the centering of the rungs 9 through the apertures in the webs of the angle members 12 and 14. The centering means comprise a bracket 70 extending from one side of the arch structure 2, serving as a pivotal mounting at 71 for a bell lever 72 having an arm projecting inwardly and curved in a position extending within the rolled section constituted by the angle member such as 14 in Fig. 8 and having a curved end 72a adapted to be engaged by the projecting end of the rung 9 as it is loosely mounted between the webs of the angle members. As the rungs are advanced into the forging position, the rungs are automatically centered by engagement of the curved end 72a of bell lever 72, and the complementary curved end 73a of the corresponding bell lever 73 mounted on the opposite side of the arch as schematically illustrated in Fig. 8a. Each bell lever is assembled in a symmetrical manner and Fig. 8 will serve to illustrate the assembly of both levers indicated more particularly in Fig. 8a. The projecting end 72b of bell lever 72 is slotted at 72c for the passage of the adjustable screw threaded rod 74, pivoted at 75 to the arch structure 2. The screw threaded rod 74 is engaged by sets of nuts 74a on one side and an adjustable gripping means 76 on the other side. By adjusting the gripping means 76 along the screw threaded rod 74 and locking the said gripping means in position by lock nut 77 the position of the curved ends 72a and 73a of bell levers 72 and 73 may be set for properly centering the rungs 9, preparatory for the forging operation, when the rung is moved to a position aligned with the outside head forming dies 33 and 34.

The several air control cylinders hereinbefore described are associated as represented schematically in Fig. 11, wherein the air controlled clamping cylinders 31 and 32 are shown in approximately the center of the diagram, with their piston rods extending inwardly for operating the outside head forming dies shown schematically at 33 and 34. The electrode operating cylinders are schematically shown at 3 and 4 in a vertical position for operating electrode carrying piston rods 5 and 6. The ejector or spreader bar air controlled cylinder is illustrated at 45 at substantially the center of the diagram, and adjacent thereto there is shown the spreader bar cylinders 62 and 63 for operating spreader bars 66

and 67 carrying anvils 68 and 69. The ejector cylinders are shown at 22 and 30 at opposite ends of the machine for respectively operating the heads 20a and 21a at one end of the machine and the heads 18a and 19a at the opposite end of the machine for simultaneously elevating the angle members into a centered position for effecting a forging operation. The interconnection of the several air controlled cylinders has been schematically illustrated in the diagram all controlled from the pressure source connected to main air supply line 78, from which the air is distributed through pipe lines 79, 80, 81 and 82 to the several groups of cylinders, as shown, and controlled by valve systems, as illustrated.

In Fig. 12 there is shown the program control circuit employed for timing the application of the heating current to the ends of the treads while in clamped position between the ladder stiles for effecting a hot upsetting operation. The power source, such as 110 volts 60 cycle alternating current, has been indicated as connected with the terminals 83 and connected to the control circuit through switches 84 and fuses 85 to the relay system, which includes across the circuit 5', 6' the cycle start contacts 21' and contacts CR1 connected through circuit element 1' with emergency stop unclamped contacts 22', connected through circuit element 2' connected to CR4 which are connected through circuit element 3' with circuit CR1. The next progressive section of the program control circuit includes contacts CR1' connected through circuit element 4' with clamp pressure switch #1' shown at PS1 connected through circuit element 7' with contacts CR2 and connected through circuit element 8' with solenoid valve "B" and the solenoid valve control circuit for positioning the angle members 12 and 14 represented at 36. The next level of the program control circuit includes contacts TDR4 and solenoid TDR4. The succeeding level of the program control circuit includes timer valve relay 87 connected through circuit elements 100' and 101' and through circuit element 9' with circuit TDR3 for controlling the weld press solenoid "C." The next level of the program control circuit includes the forge valve relay contacts represented at 88 between circuit elements 103' and 156' connected through circuit element 19' with solenoid valve "D" and circuit CR2. The next progressive level of the program control circuit contains contact CR1, circuit element 11' and solenoid valve "A" for the clamping dies 33 and 34. The next level of the program control circuit includes the heating contacts for turning the heat on and off, shown at 89 connected through circuit element 12' and circuit elements 104' and 105' to the timer contactor relay shown at 90. The circuit is completed through circuit element 13' to the contactor firing relay 91. The final level of the program control circuit contains contacts TDR3, contacts 92, circuit element 14' and relay CR4 shown at 93.

Fig. 13 illustrates the manner of applying the heating current to the ladder rungs under control of the circuit illustrated in Fig. 12, where the circuit elements illustrated in Fig. 12 have been schematically described by the same reference characters used in Fig. 12 and showing the relative sequence of the different components represented by the legends for controlling the ignitron contactor system, such as the General Electric CR7503E103 ignitron contactor, including gaseous discharge tubes 94 and 95 operating from a source of 440 volts 60 cycle power supply connected to

terminals 96 for delivering an approximately 150 kva. to the welding transformer represented at 97 shunted by the load resistor or surge suppressor 98. The circuit through the ladder rung 9 has been indicated schematically at 99. The timer has been indicated in block diagram at 100, designating, for example, a General Electric type CR7503F180 nema 5B timer, and the relay panel has been shown at 101 containing the several relays indicated by reference designations which are similar to the designations shown in Fig. 12. The contactor PS1 and the relative circuit positions of solenoids "A," "B," "C" and "D" have been indicated in Fig. 13.

In Fig. 14 the manner of effecting the clamping and forging operation has been illustrated, wherein the positive terminal of the power supply is fed to the electrodes 7 and 8, while the negative side of the power supply is fed to the outside head forming dies 33 and 34 for raising the temperature of the ends of the rung 9, according to the current flow path indicated by the arrows and enabling the hot upsetting operation to be effected as the ladder rung is subjected to axial pressure producing the headed ends 9a and 9b, as shown in Fig. 15, on the ladder rung on the sides of the webs of the angle members 12 and 14, adjacent the flanges thereof, and producing the rounded shoulders 9c and 9d on the sides of the webs which are disposed in spaced parallel relation to each other.

The method of producing ladders has proven very rapid in mass production. The upsetting of a single rung has been described, but it will be understood that the angle members constituting the ladder with the rungs loosely fitted therein are fed through the machine in successive steps for fastening the several treads in position. A complete railway car ladder including eight rungs may be fabricated in a time period averaging approximately seven minutes, utilizing the method and machine of this invention.

The machine is set in operation by activating an electrical switch, thereby clamping the preplaced ladder rung with the electrodes 7 and 8 operated from the vertical cylinders 3 and 4. The cylinders are located between the ladder stiles and operate the electrodes which form with the anvils 10 and 11 a very rigid rung clamp and also incorporate the inside rung head forming dies.

While pressure is maintained by the two cylinders 3 and 4, the two horizontal cylinders 31 and 33 which operate the outside head forming dies automatically proceed inward to the rung ends.

Through the use of a surge tank 102 (Fig. 11) for the storage of an additional supply of air over and above that furnished by the direct air-line pressure, these two cylinders 31 and 33 are held with pressure on both sides of the pistons within the cylinders to cushion the contact of the outside forming dies 33 and 34 to the ends of the ladder rung.

Just before the circuit is closed, or, in other words, just before the contact of the outside head forming dies 33 and 34 with the ends of the rung, three cylinders 45, 62 and 63, connected to fulcrum levers on each side of the dies, spread the ladder stiles 12 and 14 an amount equivalent to the metal used to shape the inside head.

Upon contact of the two outside head forming dies 33 and 34 operated by cylinders 31 and 32 with the ends of the ladder rung, the heating cycle through the electrical timers (Figs. 11-12-13) is activated. Through automatic operation of

the electrical controls at this point, the spreader bars are retracted, the air is discharged from in front of the two cylinder pistons of cylinders 31 and 32, and the upsetting of the inside and outside forged heads of the ladder rung is performed with the full capacity of approximately 100 pounds per square inch.

Then, with the forging of the ladder rung completed, and again through automatic electrical controls, all cylinders and dies are returned to a retracted, or open position. The ladder rung is ejected from the dies by two vertical cylinders 22 and 30 by pushing the ladder upward and maintaining the ladder in an upward position for pushing the ladder forward and advancing the ladder to the next run location. The loading of the ladder stiles and the ladder rungs is a manual operation, but all other operations are completely automatic.

While the method and construction of the machine has been described in one of its preferred embodiments, it is realized that modifications and changes may be made, and it is to be understood that no limitations upon the invention are intended other than may be imposed by the scope of the appended claims.

What I claim is:

1. Apparatus for fabricating metallic ladders of the type which includes a pair of spaced metallic angles having metallic ladder rungs extending between the metallic angles comprising a frame, an arch structure on said frame, means for guiding a pair of substantially parallel longitudinally extending spaced metallic angles in parallel relation beneath said arch structure, the webs of said metallic angles carrying metallic ladder rungs projecting transversely thereof and means extending transversely through said arch structure and aligned with the opposite projecting ends of the ladder rungs for gripping the projecting ends of the ladder rungs for applying axial pressure thereto, composite electrodes and anvils gripping opposite end portions of the ladder rungs in positions immediately adjacent the inner faces of the webs of the angles for maintaining said rungs in position while pressure is applied to the opposite ends thereof, circuit means connected with the electrodes of the composite electrodes, adjustable means engaging the opposite projecting ends of the ladder rungs for symmetrically centering the ends of the ladder rungs with respect to the angles prior to each upsetting operation and anvils for passing the heating current through the end portions of the ladder rungs for performing a hot upsetting operation and fastening the ends of the ladder rungs with the webs of said metallic angles.

2. Apparatus for fabricating metallic ladders of the type which includes a pair of spaced metallic angles having metallic ladder rungs extending between the metallic angles comprising a frame, an arch structure on said frame, means for guiding a pair of substantially parallel longitudinally extending spaced metallic angles in parallel relation beneath said arch structure, the webs of said metallic angles carrying metallic ladder rungs projecting transversely thereof and means extending transversely through said arch structure and aligned with the opposite projecting ends of the ladder rungs for gripping the projecting ends of the ladder rungs for applying axial pressure thereto, composite electrodes and anvils gripping opposite end portions of the ladder rungs in positions immediately adjacent the inner faces of the webs of the angles for maintaining said rungs in position while pressure is

applied to the opposite ends thereof, circuit means connected with the electrodes of the composite electrodes, adjustable means on each side of said arch structure and aligned with the ends of the ladder rungs, said adjustable means each including a pivotally mounted bell lever carried by the side of the arch structure, a shoe carried by one end of said lever and extending in the path of the ends of the ladder rungs projecting through said angles, the other end of said lever being adjustably engaged by an adjustable screw device pivotally supported with respect to said arch structure for adjusting the position of the shoe carried by said lever, whereby the symmetrically arranged shoes engage and center opposite projecting ends of the ladder rungs, preparatory for a pressure applying and current applying operation and anvils for passing the heating current through the end portions of the ladder rungs for performing a hot upsetting operation and fastening the ends of the ladder rungs with the webs of said metallic angles.

3. Apparatus for fabricating metallic ladders of the type which includes a pair of spaced metallic angles having parallel ladder rungs extending between the metallic angles comprising a frame, an arch structure on said frame, means for guiding a pair of substantially parallel longitudinally extending spaced metallic angles in parallel relation beneath said arch structure, the webs of said metallic angles carrying metallic ladder rungs projecting transversely thereof and means extending transversely through said arch structure and aligned with the opposite projecting ends of the ladder rungs for gripping the projecting ends of the ladder rungs for applying axial pressure thereto, composite electrodes and anvils gripping opposite end portions of the ladder rungs in positions immediately adjacent the inner faces of the webs of the angles for maintaining said rungs in position while pressure is applied to the opposite ends thereof, circuit means connected with the electrodes of the composite electrodes, a pair of spreader members aligned with the angles and engaged with the angles for displacing the angles to positions for shaping the inside head of the ladder rung during the heating and forming operation and anvils for passing the heating current through the end portions of the ladder rungs for performing a hot upsetting operation and fastening the ends of the ladder rungs with the webs of said metallic angles.

4. Apparatus for fabricating metallic ladders of the type which includes a pair of spaced metallic angles having parallel ladder rungs extending between the metallic angles comprising a frame, an arch structure on said frame, means for guiding a pair of substantially parallel longitudinally extending spaced metallic angles in parallel relation beneath said arch structure, the webs of said metallic angles carrying metallic ladder rungs projecting transversely thereof and means extending transversely through said arch structure and aligned with the opposite projecting ends of the ladder rungs for gripping the projecting ends of the ladder rungs for applying axial pressure thereto, composite electrodes and anvils gripping opposite end portions of the ladder rungs in positions immediately adjacent the inner faces of the webs of the angles for maintaining said rungs in position while pressure is applied to the opposite ends thereof, circuit means connected with the electrodes of the composite electrodes, a pair of spreader bars operative to engage the inside faces of the webs of the

angles for spreading the angles in a position prior to the alignment of the ladder rung carried thereby with the means for gripping the ladder rung, separate means for spreading the angles at a position located beyond the means for gripping the ladder rung, and anvils for passing the heating current through the end portions of the ladder rungs for performing a hot upsetting operation and fastening the ends of the ladder rungs with the webs of said metallic angles.

5. Apparatus for fabricating metallic ladders of the type which includes a pair of spaced metallic angles having parallel ladder rungs extending between the metallic angles comprising a frame, an arch structure on said frame, means for guiding a pair of substantially parallel longitudinally extending spaced metallic angles in parallel relation beneath said arch structure, the webs of said metallic angles carrying metallic ladder rungs projecting transversely thereof and means extending transversely through said arch structure and aligned with the opposite projecting ends of the ladder rungs for gripping the projecting ends of the ladder rungs for applying axial pressure thereto, composite electrodes and anvils gripping opposite end portions of the ladder rungs in positions immediately adjacent the inner faces of the webs of the angles for maintaining said rungs in position while pressure is applied to the opposite ends thereof, circuit means connected with the electrodes of the composite electrodes, transversely extending spreader bars mounted at opposite sides of said arch structure for engaging said angles for effecting a spreading thereof with respect to the ladder rung at the gripping and pressure applying position of the ladder rung and anvils for passing the heating current through the end portions of the ladder rungs for performing a hot upsetting operation and fastening the ends of the ladder rungs with the webs of said metallic angles.

6. In an apparatus for fabricating metallic ladders of the type formed from metallic angles

with metallic treads extending transversely of the webs thereof, which consists of a frame structure for guiding metallic angles with loosely fitting, transversely disposed metallic treads projecting therethrough, said angles being lineally movable to successive positions along said frame structure, means located at one of said positions including a pair of inwardly movable, transversely disposed, outside head forming dies for gripping opposite projecting ends of the ladder rung, means disposed above the ladder rung and constituting electrodes movable into position for gripping the ladder rungs immediately adjacent the inner faces of the webs of the said angles, 15 anvils carried by said frame structure and located below the ladder rung and in alignment with the said electrodes in a plane coincident with the transverse plane of said outside head forming dies, whereby a heating current path may be 20 established through said electrodes and through the end portions of said rungs and completed through the outside head forming dies for raising the temperature of the end portions of the ladder rung to deformation temperature and effecting a hot upsetting operation for fastening the ladder rung through the webs of the angles, means displaced at opposite sides of the hot upsetting position for engaging and spreading said angles and separate means disposed beyond the aforesaid means and remote from said hot upsetting position for engaging and displacing said angles from the aligned position thereof with said outside head forming dies.
